(57) **CLAIM**

The ornamental design for a stadium style LED grow light, as shown and described.

DESCRIPTION

FIG. 1 is a top and side perspective view of a stadium style LED grow light, showing a new ornamental design, as shown and described;

FIG. 2 is a front elevation view thereof;

FIG. 3 is a back elevational view thereof;

FIG. 4 is a right side elevational view thereof, with the left side being a mirror image and thus not separately illustrated; and,

FIG. 5 is a top plan view; the bottom is not part of the claimed design and is thus not shown.
